(57) CLAIM

The ornamental design for a sexual stimulation device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a sexual stimulation device in accordance with the new design;

FIG. 2 is a first left perspective view thereof;

FIG. 3 is a second right perspective view thereof;

FIG. 4 is a second left perspective view thereof;

FIG. 5 is a top perspective view thereof;

FIG. 6 is a second right perspective view thereof; and,

FIG. 7 is a bottom perspective view thereof.

1 Claim, 7 Drawing Sheets
(7 of 7 Drawing Sheet(s) Filed in Color)
